UNITED STATES PATENT OFFICE

JOSEPH PHILIPPE PARADIS, OF LONGUEUIL, QUEBEC, CANADA

FAUCET

Application filed April 14, 1926, Serial No. 101,920. Renewed February 11, 1929.

The invention relates to a faucet as described in the present specification and illustrated in the accompanying drawings that form part of the same.

5 The invention consists essentially of the novel features of construction pointed out broadly and specifically in the claims for novelty following a description containing an explanation in detail of an acceptable 10 form of the invention.

The objects of the invention are to economize in the consumption of water particularly in very large cities, where there is a continual menace to the public in regard to 15 water famines due to the heavy consumption during the summer months and the immense wastage through the constantly open taps in houses, public buildings, offices and other places; to eliminate the inconveniences of 20 what are known as spring taps, whereby the hand basin must be filled or partially filled before the hands can be washed, whereas in the present invention the valve may be held in its open position during the operation of 25 washing the hands and immediately closed without the necessity of filling the basin, this being common practice to wash the hands at a tap with running clean water; to afford convenience to the householder and others 30 where comparatively large quantities of water are required, such as in the bath, and in the tubs used for washing purposes, by furnishing means of holding the valve open notwithstanding the automatic spring close- 35 sure device; to accomplish these purposes with a very reliable construction, which will not increase the cost of production in large quantities, thus enabling this faucet to be used universally without respect to persons 40 in regard to their possessions; and generally to provide a serviceable and durable, as well as economical faucet that may be maintained in good condition at a very low cost and inexpensive in the matter of production.

45 In the drawings, Figure 1 is a side elevation of the faucet.

Figure 2 is a vertical sectional view showing the working parts and the valve closed.

50 Figure 3 is an enlarged vertical sectional

view of the faucet showing the valve open by means of the lower thumb button.

Figure 4 is an enlarged sectional view of the spout showing the valve open by means of the upper push cap. 55

Figure 5 is a detail showing the lower spring button and connecting bar in elevation.

Figure 6 is a detail showing a plan view of the upper push cap. 60

Figure 7 is a detail showing the spring adjusting plug.

Figure 8 is a detail of the valve in elevation.

Figure 9 is a detail of the intermediate bearing. 65

Figure 10 is a detail of the adjusting key. Like numerals of reference indicate corresponding parts in the various figures.

Referring to the drawings, the numeral 10 indicates the spout of the faucet, from which 70 extends the barrel 11 having the threaded end 12 and the wrench grip 13.

The barrel 11 forms in the interior a Venturi tube having the inner wall 14 converging to a narrow passage 15 from which it flares outwardly into the spout 10. 75

The spout 10 extends upwardly at 16 from the barrel 11 and downwardly at 17, the upper part being threaded internally at 18, 80 and having a locking pin 19 projecting from the outer periphery.

The lower part 17 also forms a Venturi tube, having the inner wall 20 converging to the central passage 21 and flaring outwardly 85 therefrom to the outlet 22, the outer flare of the wall forming a valve seat 23.

The valve 24 is of cone shape and may be of any suitable material, though for the sake of cheapness and maintenance in construction rubber is possibly the best material. 90

This valve 24 has a central orifice 25 therethrough, and is mounted on the tubular stem 26, this stem being threaded internally at 27 from the lower end upwardly, and at the upper end being slidably mounted in the plug 28, which is centrally recessed from the under side at 29 to form a bearing for the upper end of said valve stem. 95

The plug 28 is externally threaded at 30 100

and screws into the thread 18 within the upper part of the spout and is preferably formed in the upper surface thereof with the radially arranged key holes 31 and the central rod orifice 32 therethrough surrounded by the packing gland 33.

The intermediate bearing 34 for the tubular stem 26 is supported below the barrel 11 by the spider 35, therefore the said tubular stem is properly guided and maintains said valve 24 centrally on its seat 23.

The spiral spring 36 at its upper end is secured to the plug 28 in the bed of the recess 29 and at its lower end is secured to the screw plug 37 which is inserted in the threaded lower end 27 of tubular stem 26 being screwed inwardly therein to the desired position for the tension of the spring 36 in holding the valve 24 to its seat.

The adjustment of the spring 36 is accomplished by means of the key 38, which is inserted in the key slots in the plug 28 and the latter unscrewed a thread or two, which increases the tension of the spring and pulls the valve 24 tightly to its seat 23, thereby effectively stopping any leak that may occur through long use. If the valve itself is not holding the water back, it may be changed more readily than a tap washer, under the present system.

The lower thumb push button 39 has a connecting bar 40 extending therefrom and upwardly offset at its inner end 41 to receive the screw plug 42 which is screwed into the lower end of the tubular stem 26 thereby bringing the push button 39 into the desired position preferably in front of the faucet, so that it can be held by the thumb with one hand or in any other convenient way and thereby pull the valve 24 from its seat 23 against the tension of the spring 36, and thus effect the opening of the faucet for the delivery of water or other liquid under pressure.

The push cap 43 at the upper end is mounted on the upper part 16 of the spout 10, and is formed with the arc shaped key slots 44 and 45 and the flange 46, the latter having the L-shaped locking slot 47 through which the pin 19 projects.

The operating rod 48 is secured centrally in the push cap 23 and projects downwardly therefrom into engagement with the plug 37, so that on pushing the cap 43 downwardly the tubular stem 26 is carried downwardly therewith and this forces the valve 24 from its seat 23 and opens the faucet. The cap 43 may be locked by turning said cap and so bringing the locking pin 19 into the upper horizontal portion of the locking slot 47 and thereby maintain a stream of water from the faucet without the necessity of holding it to its open position.

In the operation of this invention the water or other fluid flows into the barrel 11 into the spout 10. The valve within the spout can be

operated by the push button 39 which is pressed thereby removing the valve from its seat and allows the water to pour out on to the hands of the user, and when the pressure is relieved the spring draws the valve back on the seat 23 and thereby securely closes the faucet.

If it is desired to fill a bath, then the push cap 43 is pressed down and the said cap turned to lock the pin 19 in place and thereby keep the valve 24 away from its seat until such time as the bath is filled, and then the faucet can be put back in the same position for the operation of the lower push button.

To adjust the spring the key 38 is inserted through the arc slots 44 and 45 into the key slots of the plug 28 and the latter turned to increase the tension of the valve 24 on its seat 23, and thus maintain a close fit and no leakage.

The advantages of this invention are manifest to those who use public wash rooms, where spring taps are inconvenient, for it is desirable with most people to use running water for cleansing the hands instead of a basin of water, and in order to have running water an ordinary spring faucet is not feasible, and the wastage of water is simply tremendous, and as it has become a serious matter in the larger centres it is thought that the saving of this waste by means of this faucet will prove of lasting benefit to the communities.

What I claim is:—

1. In a faucet, a barrel having a spout therefrom, a valve seat beyond said barrel in said spout, a valve mounted on said seat, a screw plug screwed into the upper end of said spout and forming an adjusting member, a spring extending from said plug to said valve and holding the latter to its seat and means extending from said valve for removing it from its seat.

2. In a faucet, a barrel extended to form a spout, the latter projecting above and below said barrel and having an inwardly converging and diverging wall forming a valve seat, a valve engaging said seat, a plug, screw threaded into the upper portion of said spout, a stem extending from said valve slidably arranged in said plug, and a spring secured to said plug, and engaging said stem and a lower push button connected with said valve and situated adjacent to the delivery end of the spout.

3. In a faucet, a barrel extended to form a spout, having a valve seat beyond said barrel, a valve on said seat, a tension spring secured in the upper end into said valve, a lower push button connected with said valve for drawing it from its seat against the spring pull, and an upper push member for forcing said valve from its seat and maintaining it therefrom until released.

4. In a faucet, a barrel having a spout

therefrom, a plug screwed into said spout at the upper end, and having a stem bearing, a seat in said spout in the lower portion, a valve on said seat, a stem extending through said valve and threaded at the lower portion, a spring within said stem and secured thereto, and secured at the upper end to said plug, a lower push button having a connecting bar screwed into the lower end of said stem.

5 5. In a faucet, a barrel having a Venturi tube formation therewithin and extended to form a spout, having a similar formation, the latter forming a valve seat, a valve on said seat, a tubular stem extending through said valve and threaded internally from its lower end, a plug screwed into the upper end of said spout and having a bearing for said tubular stem, and an intermediate bearing for said tubular stem in spout, a push cap for the upper end of said spout, having a locking slot therethrough and key slots through the top thereof, a rod secured centrally to said push cap and extending down said stem, a spiral spring encircling said stem and secured to said plug at its upper end and secured to the screw plug inserted in said stem from the lower end, and engaging the lower end of said rod, and a lower push button having a connecting rod screwed into the lower end of said stem.

30 6. In a faucet, a barrel extended to form a spout, the latter having a valve seat, intermediate between the barrel and the delivery end, a screw plug introduced in the upper end of said spout and having key slots in the upper surface thereof, and a central rod orifice therethrough surrounded by a packing gland, a push cap for said upper end of the spout, having a locking slot and pin therethrough into said upper end, and arc shaped slots through the top for the insertion of an adjusting key into the aforesaid key slots, a rod secured centrally into said push cap and extending downwardly therefrom through said orifice and packing gland, a valve stem having a screw plug and a spiral spring extending from said plug and encircling said rod, and secured at its upper end to the spring adjusting plug screwed into the upper end of the spout, a valve on said stem engaging said seat, and a lower push button having a connecting bar therefrom offset at its inner end and screwed into the lower end of said stem.
